UNITED STATES PATENT OFFICE.

HERMAN J. SELK, OF SPOKANE, WASHINGTON.

LOCKING DEVICE.

1,160,535.

Specification of Letters Patent.

Patented Nov. 16, 1915.

Application filed October 27, 1914. Serial No. 868,853.

To all whom it may concern:

Be it known that I, HERMAN J. SELK, a citizen of the United States, residing at Spokane, in the county of Spokane and State of Washington, have invented certain new and useful Improvements in Locking Devices, of which the following is a specification.

The object of this invention is to provide an improved form of locking device wherein reliance is placed upon engagement of structural parts against each other for locking a supported body against relative movement in one direction with respect to its supporting body.

My invention more particularly consists in providing a cylinder head or like part with a truly semi-circular recess which is struck from one center which has a single radial length as regards all curved portions of the recess. The end of the tube bar, which may be properly termed a "supporting body", is likewise provided with a peripheral portion struck from a single center, 25 of a single radius, and proportioned to fit said recess. Thus all of the recesses of all of the cylinder heads made, will be standard, and can be drilled out at a single operation by holding the cylinder heads in flat 30 abutting relation and forcing a drill through all of the heads at one time.

In the most improved embodiment of my invention, the stop portions of the recesses are tangentially disposed and extend from 35 a point inside of the periphery of the head to a point intersecting the latter, the segmental heads being provided with complementally formed and tangentially disposed stops for engaging the stops of the recesses, the latter preferably being cavities and the former projections.

Other objects and features of the invention will be more fully described in connection with the accompanying drawing and 45 will be more particularly pointed out and ascertained in and by the appended claims.

In the drawing:—Figure 1 is an end view showing a cylinder head equipped with the device of my invention. Fig. 2 is an end 50 view of one of the tooth supporting bars showing the contour of the segmental end of the bar. Fig. 3 is a view in side elevation looking in the direction of arrow 3 of Fig. 2. Fig. 4 is a perspective view on 55 an enlarged scale of a portion of a cylinder head showing the formation of the segmen-

tal recess. Fig. 5 is a view in elevation, partly in section, showing a modified form of the invention. Fig. 6 is a sectional view looking in the direction of arrow 6 of Fig. 5.

Like characters of reference designate similar parts throughout the different figures of the drawing.

As illustrated, and referring more particularly to Figs. 1 to 4, 1 designates one of the heads of a threshing cylinder in the periphery of which is formed a plurality of equi-distantly spaced recesses 2. Each recess, as will be more particularly seen by reference to Fig. 4, consists of a substantially rounded or cylindrical cavity of slightly more than a semi-circle, as indicated as a whole at 2. The recess opens into the peripheral face 3, of the cylinder head 1, and is shown extending transversely through the head, thereby forming an open ended recess. The mouth or entrance of the recess, as indicated at 4, is somewhat reduced with respect to the greatest dimension of the recess, as indicated at 5, so that when the segmental tooth bar end is positioned in the recess, it will be effectively prevented from being dislodged radially therefrom. In order to prevent the segmental rod ends from turning or rotating in one direction, when 80 they are seated in their recesses, each recess is provided with one or more stop portions, two being shown, which are in the form of flattened faces 6. The flattened faces or portions 6 are disposed tangentially with 90 respect to the interior face 7, of their recess, and are shown as extending from within the periphery 3 to a point intersecting the periphery 3. Furthermore, it will be noted that the tangential stop portions 6 are 95 relatively reduced in width with respect to the total width of the cylinder head 1 so as to leave a central portion 8, forming a continuation of the semi-circular face 7. At one point in the recess is drilled or otherwise formed a holding socket 9, as clearly indicated in Fig. 4. The direction of rotation of the threshing cylinder is indicated by the arrow shown in Fig. 1, and attention is directed to the fact that the stop portions 6 face in the direction of rotation of the cylinder, a point which will presently be more clearly understood.

Tooth bars are indicated at 10 and cylinder teeth 11 may be mounted upon the bars 110 in any desired manner. The ends of the bars, as indicated at 12, are shown some-

what enlarged with respect to the cross section of the bars 10 and are shaped to conform to the contour of the cavities or recesses 2 for insertion and anchorage therein. By reference to Fig. 2, it will be seen that the ends 12 constitute a segmental head of more than a semi-circle, the flat outer face 13 being adapted to lie flush with the periphery of the cylinder head 1. Insertion of the segmental bar head 12 into the recess 2, is effected by tilting the bars in the direction of rotation of the cylinder 1, as indicated by the tilted position of one of the bars in Fig. 1. The bar will then be turned 15 in a direction opposite to the direction of rotation of the cylinder 1 until it attains the position occupied by the remainder of the bars of Fig. 1. Now the thrust due to working action of the threshing cylinder under load, tends to force the teeth in the direction of arrow *a*, of Fig. 1, and it is with a view of effectively supporting the tooth bar against such movement, by abutting rigid parts; that the present invention is addressed.

The segmental heads 12 are provided with tangentially disposed projections 14, which are shaped to engage the tangential stops 6 and which, as will now be seen, face in a direction opposite to the direction of rotation of the threshing cylinder. The projecting stops 14 are each equal in width to the recess stops 6 so that there is an intervening portion 15, between the stops 14, for receiving that portion 8 which is a continuation of the semi-circular recess face 7.

Now it will be clearly seen that when the male or projecting stops are moved into a final position so that they lie upon opposite sides of the portion 8 of the recess, that it will be impossible for the tooth bars to have any longitudinal play whatsoever, the bar being locked against turning movement in one direction and against longitudinal movement in either direction. In practice, the stress imposed upon the teeth 11 to rock the bars in the direction of the arrow *a*, will have a tendency to tightly jam and anchor the segmental heads 12 in the recesses 2, however, in case the cylinder were reversed, in its direction of motion, because of clogging or choking by an excess of straw, then the bars might possibly become loosened.

I therefore provide means which may be in the form of a bolt 16, threaded through the head 12 and projecting into the socket 9, which serves to prevent movement of the tooth bars in the direction of arrow *b*. However, the engagement of the bolt 16 with the socket 9 is not sufficiently tight to wholly sustain the tooth bars against turning movement in the direction in which load or stress is applied and therefore the bolt 16 does not in any sense take the place of or supplement the stops 6 and 14 as the parts are so ar-

arranged and proportioned that the bolt 16 will not act to take up stress in the direction of arrow *a*.

In Figs. 5 and 6, I have shown a modified form of the invention in which the cylinder head 17 is equipped, preferably on its inside face, with a stop segment or portion 18.

The bar 19, on which the teeth are carried, is provided with an end or head 20 which is shown flattened on one side. The head 20 is provided with a stud 21 for engagement with the end of the segmental stop 18 to resist turning movement of the head in the recess 22, beyond a predetermined extent. The stop portions 21 and 18 function in the same manner as the stop portions 15 and 14 but are of a different formation. The stop 21 is provided with a shank 23 which may be inserted in the head 20 so that in case of breakage, the stop 21 could be renewed without requiring renewal of the entire bar 19. The head 20 is shown provided with a bolt 24, the function of which is similar to that of bolt 16.

A feature common to both forms of the invention shown, consists in the flat abutting faces which are brought in flat engagement against each other to resist movement of the tooth bars in one direction, which is the direction in which stress is imposed.

While I have herein shown and described the device of my invention as applied to the tooth bar of a threshing cylinder, it will be understood that broadly considered, the ends of the tooth bar comprise the supported elements, while the cylinders with their segmental recesses comprise the supporting elements, in accordance with the utility to which the device is applied.

It is believed that my invention will be clearly understood from the foregoing description and while I have herein shown and described specific forms thereof, I do not wish to be limited thereto except for such limitations as the claims may import.

I claim:

1. A cylinder head having a peripherally disposed segmental recess greater than a semi-circle and one terminal portion of the face of said recess being cut away outwardly from said recess at opposite margins of the recess to form laterally disposed stops, and a segmental supporting body proportioned to fit in said recess and having laterally disposed stops projecting from its periphery for engagement with the cut away stops of said recess to arrest turning movement of said segmental body in said recess under working thrust beyond a predetermined extent and lock said body against lateral movement in said cylinder head, substantially as described.

2. A cylinder head having a peripherally disposed segmental recess greater than a semi-circle and being struck from a single

center with a single radius and having a stop portion formed in said recess, and a segmental supporting body having a periphery struck from a single center with a single radius and proportioned to fit said recess and said body having a stop portion formed in its periphery for engagement with the stop of said recess to arrest turning movement of said body in said recess under working thrust, substantially as described.

3. A cylinder head having a peripherally disposed segmental recess greater than a semi-circle and being struck from a single center and one portion of said recess being 15 cut away to form a stop portion disposed tangentially to said recess, and a segmental supporting body having a peripheral portion struck from a single center and provided with a stop projecting from its periphery and disposed tangentially thereto for engagement with said cut away stop to 20

arrest turning movement of said body in said recess under working thrust, substantially as described.

4. A cylinder head having a peripherally 25 disposed segmental recess greater than a semi-circle and being struck from a single center with a single radius, and a segmental supporting body having a periphery struck from a single center with a single radius 30 and proportioned to fit said recess, said body and head having coacting portions for preventing rotation of said head with respect to said body, substantially as described.

35 In testimony whereof I affix my signature in presence of two witnesses.

HERMAN J. SELK.
